(57) **CLAIM**

The ornamental design for a fingerboard practice accessory having simulated strings as shown and described.

DESCRIPTION

FIG. 1 is a front perspective view of the fingerboard practice accessory having simulated strings of the instant invention; FIG. 2 is a left side elevational view thereof; FIG. 3 is a right side elevational view thereof; FIG. 4 is a front elevational view thereof; FIG. 5 is a rear elevational view thereof; FIG. 6 is a top plan view thereof; FIG. 7 is a bottom plan view thereof; FIG. 8 is a perspective view thereof, illustrating the design in an alternate use as an eating utensil and positioned on a table environment; and, FIG. 9 is a front perspective view thereof, illustrating the design in an alternate use as a pointer instrument. The broken lines are for the purpose of illustrating portions of the article that form no part of the claim.
